JIG GRINDER

Henry E. Durkee, Manchester, Conn., assignor to
 Niles-Bement-Pond Company, West Hartford,
 Conn., a corporation of New Jersey

Application September 15, 1948, Serial No. 49,359

5 Claims. (Cl. 51—43)

1

This invention relates to grinding machines and particularly to a precision grinding machine adapted for grinding internal cylindrical and conical surfaces of varying diameter.

More particularly the invention relates to an internal or hole grinding machine adapted to grind tool locating holes in hardened plates forming parts of drill positioning, or other types of jigs and fixtures, the material of which the plate is made being unadapted for conventional precision boring or drilling operations.

More specifically the invention relates to an internal grinding machine of the planetary type in which the grinding wheel, in addition to rotation about the axis of its own spindle, is revolved about an axis parallel thereto, the distance between these axes being manually adjustable at any time during the grinding operation to vary the diameter of the hole being ground.

A feature of importance of the invention is that the grinding wheel is rotatably mounted on the lower end of a spindle forming an extension of the armature shaft of a small high speed electric motor mounted within a suitable head, the head carrying the motor and spindle being laterally adjustable within and revolvable about the axis of a cylindrical slide on the lower end of which it is mounted, the reciprocatory movements of the slide being parallel to the axis about which the head and spindle revolve in any lateral adjustment of the head and within a rotatable trunnion.

A primary object of the invention is to provide means for reciprocating the slide carrying the tool head between adjustable limited vertical positions while the head carrying the grinding wheel is being revolved about the axis of its supporting member within the slide and while the grinding spindle is being rotated by its motor about its own axis.

Another object of the invention that is important is that the lateral adjustments of the grinding wheel and its spindle to vary the diameter of the hole being ground may be made at any time during the grinding operation to vary the size of the hole being ground, and that the vertical movements of the slide and the current supply to the wheel motor is not interrupted by adjustments of the wheel spindle.

And finally it is an object to provide angular adjustments for the vertically slidable member within the rotating supporting carriage for the purpose of grinding conical holes.

The objects and features enumerated above

2

are incorporated, in the embodiment of the invention illustrated in the drawings, in a machine tool the wheel spindle of which is vertical and the work supporting table for the machine tool is movable to predetermined precise positions in directions at right angles to each other in a horizontal plane.

With the above and other objects in view the invention may include the features of construction and operation set forth in the following specification and illustrated in the accompanying drawings.

In the accompanying drawings annexed hereto and forming a part of this specification, I have shown the invention embodied in a precision hole grinding machine of large size and for a wide range of hole diameters, but it will be understood that the invention can be otherwise embodied and that the drawings are not to be construed as defining or limiting the scope of the invention, the claims appended to this specification being relied upon for that purpose.

In the drawings:

Figure 1 is an outside view in front elevation of a complete grinding machine embodying the present invention.

Fig. 2 is a similar view in side elevation of the machine shown in Fig. 1, the view being taken from the right.

Fig. 3 is a side elevation partly in section showing portions of the mechanism for laterally adjusting the grinding wheel head.

Fig. 3^a is a section showing the manual means to actuate the wheel feeding mechanism.

Fig. 4 is a central vertical sectional view of parts shown in Fig. 3.

Fig. 5 is a vertical sectional view of the upper portion of the vertically movable wheel head spindle and its supporting and rotating means, showing also the angular adjustment for the vertically movable spindle within the trunnion.

Fig. 6 is a partially broken away view of the lower end of the wheel head spindle, the wheel head rotating motor, and wheel spindle.

Fig. 7 is another view of the parts shown in Fig. 6, showing the lateral adjusting means for the grinding wheel head.

Fig. 8 is a side elevation of some of the parts shown in Fig. 4.

Fig. 9 is a sectional view of parts shown in Fig. 5, the section being taken at 90° from that in Fig. 5.

Fig. 10 is a vertical sectional view of the means to raise and lower the wheel and its attached parts.

In the above-mentioned drawings, I have shown but one embodiment of the invention which is now deemed preferable, but it is to be understood that changes and modifications may be made within the scope of the appended claims without departing from the spirit of the invention.

Briefly, and in its preferred aspect, the invention may include the following principal parts: First, a base having a column rigidly fixed at one side thereof; second, a work supporting table movable on said base in a horizontal plane in directions at right angles to each other; third, precision locating means for said table in its directions of movement; fourth, a vertically adjustable carriage on said column; fifth, means to adjust said carriage to positions accommodating the machine for work of various heights; sixth, a trunnion within said carriage rotatable upon a vertical central axis; seventh, a spindle within the trunnion supported within a sleeve which may be tilted relative to the axis of rotation of the trunnion having a wheel supporting head at its lower end laterally adjustable to the axis of rotation of said trunnion; eighth, means to tilt said sleeve and its spindle to slightly oblique adjustable positions relative to the axis of rotation of said trunnion; ninth, a motor mounted within said head having a vertically disposed armature shaft; tenth, a grinding wheel mounted on the extended lower end of said armature shaft; eleventh, circuits and controlling means for said motor; twelfth, manually operated means to adjust the lateral position of said motor and spindle during reciprocating movements of the head and rotating movements of the trunnion; and thirteenth, means to rotate the trunnion about its vertical axis to revolve the grinding head and wheel motor in circles of predetermined radii.

Referring more in detail to the figures of the drawing, a preferred embodiment of the invention is shown in which a base 10 having a vertically extending column 12 at one side supports a vertically adjustable carriage 14 upon suitable guideways 15 formed on the column 12. Within this carriage 14 is a trunnion 16 rotatably mounted on a vertical central axis preferably on spaced ball bearings 18 as shown.

The trunnion is slowly rotated by means presently to be described and supports a vertically movable spindle or slide to which the wheel head is attached at its lower end. The spindle is movable up and down by mechanical means during operation to traverse the wheel along the hole being bored.

Means to raise and lower the carriage 14 and to slowly rotate the trunnion 16 about its axis will presently be described. Within the trunnion 16 is an elongated sleeve 20 mounted for tilting movement about aligned centers 22 near its lower end and within which the spindle 26 is slidable (see Figs. 5 and 9). To adjust the oblique position of this sleeve 20 and spindle 26 relative to the axis of trunnion 16 an adjusting screw 24 is attached to the sleeve 20 adjacent its upper end and engaging a connection on the trunnion 16. By rotating a nut 27 forming part of this connection the sleeve 20 may be accurately adjusted to any tilted position as indicated by the scale 25. To clamp the sleeve 20 in its adjusted tilted position, clamping bolts 29, one only of which is shown, may be mounted on fixed members secured to the top surface of the trunnion 16.

The sleeve 20 pivots about the axis of aligned pins 22 the pointed inner ends of which enter

conical recesses within the sleeve. To adjust the pins 22 threaded screws 31 may engage their outer ends and provide axial adjustment of the pins 22 to firmly support the sleeve 20 and its attached parts.

The carriage 14, as stated above, is vertically movable on the column 12 and for adjusting the carriage to different vertical positions a small individual motor 40 (see Fig. 1) is provided to rotate a small pinion 42 rotatably mounted in the column 12 and in engagement with a vertical rack 44. Clamping means may be provided to secure the carriage 14 in any adjusted vertical position on the column 12 and during grinding operations the carriage 14 is preferably retained in fixed vertical position.

Within the sleeve 20 operates the upper extended end of spindle 26 for a grinder head 28 presently to be more fully described. The spindle 26 for the head 28 is splined as shown at 33 in Fig. 5 to the sleeve 20 and coaxial therewith, and is vertically movable between adjustable limiting positions by suitable power means. Anti-friction bearings 30 may be provided engaging the walls 25 of the spindle or supporting member 26 for the head 28 and the sleeve 20. Within the head 28 is the wheel rotating motor 50 mounted for precision manual transverse adjustments during operation and having an abrasive wheel 52 on the lower end of its motor spindle preferably forming the extended shaft of the armature of the wheel motor. These elements will now be described.

As shown most clearly in Figs. 6 and 7, the motor 50 is laterally adjustable upon suitable straight line anti-friction bearings 54 formed on the lower surface of the head 28. To effect lateral adjustments of the motor 50 and its spindle to feed the abrasive wheel 52 laterally relative to the work, its supporting plate 56 carries a fixed screw 58 extending in a central horizontal plane and engaged by a rotatable nut 60. The axis of this fixed screw 58 intersects the axis of the spindle 26. The nut 60 is retained against axial movement relative to the head 28 within the lower end of the spindle and is provided with bevel gear teeth. Meshing with these gear teeth on nut 60 is another bevel gear 62 rotating on a central vertical axis and housed within the member 26. Rotation of these gears 58 and 62 will therefore transversely adjust the wheel motor 50 and its abrasive wheel 52. Connected to this gear 62 through suitable universal joints and an elongated shaft 63 is an operating gear 64, this latter gear, as shown in Fig. 3 and the diagram, Fig. 11, being at the upper end of the shaft 63. To rotate this gear 64 to rotate the nut 60 and laterally adjust the motor 50 during operations to feed the wheel 52 toward the surface of the hole by means of the screw 58, connections are provided presently to be described.

On a forwardly extending horizontal surface of the base 10 is provided a saddle 29 movable in a horizontal plane on suitable ways directly toward and from the column 12. On the upper surface of the saddle 29 on suitable ways extending at right angles to the ways on which the saddle 29 operates is a transversely and horizontally movable table 35 on which work pieces 65 may be mounted. Traversing and indicating means are provided for accurately positioning the saddle 29 and table 35 manually to successive positions for operations upon different parts of a work piece (not shown) secured to said table 35. As these positioning and indicating means for the

saddle and table are or may be similar to those shown, in patent to Hanson 1,323,267, granted December 2, 1919, a further description of them is not thought to be necessary. By means of a hand wheel 37 on the forward end of a screw 34 the saddle 29 may be moved toward and from the column 12 and by a second hand wheel 39 at one side of the machine on the end of a screw 38 the table 35 may be moved laterally relative to the saddle 29.

With work pieces moved successively to different positions by adjustments of the saddle 29 and table 35 as called for by the work piece being operated on, the wheel 52 can be moved up and down by movements of the slide 26 during rotation of the trunnion 16. During this operation the revolving movement of the wheel 52 can be adjusted to different radii to grind the hole in the work piece to any desired diameter.

These feeding movements of the wheel 52 are required during rotation of the trunnion 16 to revolve the wheel in planetary paths of slightly increasing radii. Connections are therefore provided to a fixed position on the carriage 14 so that the operator may, as required, make the necessary adjustments manually from this position. At the upper end of the sleeve 133 is a gear 46 concentric to gear 64 previously referred to and meshing with a smaller gear 66 on the lower end of a shaft 68 rotatably mounted within a planetary housing member 70. At the upper end of this shaft 68 is a gear 72 meshing with a gear 74 of equal size on a short shaft 76 within the housing member 70 of the planetary mechanism. This short shaft 76 carries a second gear 78 meshing with a larger gear 80 on the upper end of a sleeve 82 surrounding the first shaft 68. This sleeve 82 at its lower end carries a gear 84 meshing with the gear 64 on the upper end of the shaft 63. The ratios of the above gearing is such that with no rotary movement of the planetary housing member 70 rotation of the trunnion 16 and the gear 46 will have no rotative effect upon the wheel adjusting shaft 63. Gears 46 and 64 will therefore rotate together without any relative rotation. If, however, rotation is imparted to the planetary housing 70 as by means of a gear 86 secured thereon, the wheel adjusting shaft 63 will be rotated relative to the trunnion 16. This movement will effect feeding movements of the wheel. To rotate the gear 86 on the planetary housing 70 a vertical shaft 85 having a gear 88 splined thereto at its upper end is drivingly connected to the gear 86. At the lower end of the shaft 85 is a manual operating means for slowly rotating the shaft. Preferably two speed ratios between the shaft 85 and hand wheel 89 are provided, one of which is through intermeshing helical gears 91 and the other through a worm and worm gear drive 93. By an intermediate clutch 87 on the shaft 85 a fast or slow driving connection is obtained.

To rotate the trunnion 16 about its axis to revolve the wheel 52 in a planetary path, the following mechanism is provided. On the trunnion 16 as shown in the diagram (Fig. 11) is a large gear 90 meshing with a pinion 92 on the upper end of a shaft 94. The lower end of this shaft 94 is provided with suitable clutches 96 and with a gear 98 meshing with a gear 100 on the lower end of a vertical shaft 102 extending alongside the trunnion 16. This shaft 102 at its upper end carries a bevel gear 104 meshing with a companion bevel gear on a horizontal shaft 106. At the opposite end of this latter shaft 106 connected

through suitable gears 108 is a vertical shaft 110 alongside the column 12 and connected through any form of speed change gearing 112 to the driving motor 114. A telescopic joint in one of the vertical shafts (not shown in the diagram) permits adjustment of the carriage 14 and trunnion 16 to different vertical positions without interruption of the rotating means.

The manual reciprocating means for the head 10 and spindle 26 and parts connected thereto during operation and rotation of the trunnion 16 includes a rotatable nut 120 supported for rotation about a vertical screw 122 but retained against axial movement relative to the head 17 movable with spindle 26 within which it is mounted. Manual means are provided for rotating the nut 120 including a gear 124 on the nut meshing with a gear 126 on the upper end of a vertical splined shaft 128. The lower end of this shaft 128 by meshing helical gears drivingly connects a forwardly extending shaft having a hand wheel at its forward end.

To reciprocate the head 17, wheel 50 and spindle 26 by power, means are provided for rotating the screw 122 engaged by the nut 120. The screw 122 is rotatably mounted and held against axial movement relative to the carriage 14, the trunnion 16 and parts supported thereby. This screw 122 by suitable connections including a spline shaft 130 and a speed changing mechanism (not shown) is rotated by a motor alongside the column 12. Between the splined shaft 130 and its driving motor are bevel gears 140 connecting the shaft 130 to a horizontal shaft 142 which in turn is connected to the motor by vertical shaft 144. Gears 140 and shaft 142 are, as shown in Fig. 10, housed within a member 13 fixed to the column 12.

To control the vertical movements of the head 17, movements of the spindle 26 within the trunnion 16, the vertical movements of wheel 52, and also control the rotative movement of the trunnion 16, control stations 146 and 148 respectively are provided at a convenient position for the operator.

To supply the motor 50 for the wheel 52 with current, leads 131 from any suitable source may be connected to slip rings 132 on the upper end of the sleeve 133 within head 17 and rotating with the trunnion 16 and spindle 26. These rings 132 are connected to the motor 50 by wires extending within the spindle 26 at one side of the shaft 63 for varying the lateral position of the motor 50 and the wheel 52. To accommodate these lateral movements of the motor 50 the shaft 63 is made up of several lengths extending between suitable universal joints 134. And also to accommodate this movement of the wheel and the tilting movement of the spindle 26 and its sleeve 20 there are provided universal joints 136 between the sleeve 133 and the spindle 26. By this means the upper end of the rotating members, including the sleeve 133, are mounted within the upper end of the head 17 for rotation on a fixed axis as shown in Fig. 4.

From the above described construction it will be seen that the wheel may be rotated at high speed about a vertical or slightly inclined axis by its motor while being slowly revolved with the spindle and trunnion about an axis parallel thereto at any predetermined distance therefrom by adjustment laterally of the motor and its mounting. Simultaneously with this rotary and revolving or planetary movement of the wheel, the spindle wheel head and wheel may be axially

reciprocated between adjustable limits by vertical movement of the spindle within the trunnion and slide on the column.

What I claim is:

1. An internal grinding machine comprising in combination, a base, a work supporting table movably mounted thereon, a column on said base, a carriage adjustable vertically on said column, a trunnion rotatably mounted within said carriage, a rotatable wheel head spindle axially and angularly adjustably mounted within said trunnion, angular adjusting means on said trunnion to tilt said spindle about a horizontal axis in said trunnion to oblique positions relative to the axis of rotation of said trunnion, a radially adjustable wheel head supported at the lower end of spindle, manual means extending centrally through said trunnion and spindle to adjust the radial position of said wheel, a motor within said head and radially adjustable therewith, and a grinding wheel driven by said motor.

2. An internal grinding machine comprising in combination, a base, a work supporting table movably mounted thereon, a column on said base, a carriage adjustable vertically on said column, a trunnion rotatably mounted within said carriage, a rotatable wheel head spindle axially and angularly adjustably mounted within said trunnion, angular adjusting means on said trunnion to tilt said spindle about a horizontal axis in said trunnion to oblique positions relative to the axis of rotation of said trunnion, a radially adjustable wheel head supported at the lower end of spindle, manual means extending centrally through said trunnion and spindle to adjust the radial position of said wheel, a motor within said head, and a grinding wheel on the armature shaft of said motor.

3. An internal grinding machine comprising in combination, a base, a work supporting table movably mounted thereon, a column on said base, a carriage adjustable vertically on said column, a trunnion rotatably mounted on a fixed axis within said carriage, a rotatable wheel head spindle axially and angularly adjustably mounted within said trunnion, manually operated adjusting means on said trunnion to tilt said spindle about a horizontal axis in said trunnion to oblique positions, a wheel head adjustably supported on transverse ways provided at the lower end of spindle, means to manually adjust said wheel head laterally along said ways during rotation of said spindle, said means including a planetary gear train driven by rotation of said trunnion, a vertical shaft extending through said spindle and driven thereby, and manual means to bodily rotate said planetary gearing about an axis parallel to said shaft to rotate said vertical shaft to effect said lateral adjustments of said wheel head.

4. An internal grinding machine comprising in combination, a base, a work supporting table movably mounted thereon, a column on said base, a carriage adjustable vertically on said column, a trunnion rotatably mounted on a fixed axis within said carriage, a rotatable wheel head spindle axially and angularly adjustably mounted within said trunnion, manually operated angular adjust-

ing means on said trunnion for said spindle to oblique positions relative to the axis of rotation of said trunnion, a wheel head adjustably supported on transverse ways at the lower end of spindle and having a grinding wheel spindle thereon, means to manually adjust said wheel head laterally along said ways during rotation of said spindle, said means including a planetary gear train driven by said trunnion rotation, a vertical shaft extending through said spindle and driven thereby and connected to the lateral adjusting means for said wheel head, a rotatably mounted casing enclosing said planetary gearing, and manual means to rotate said casing and planetary gearing about an axis parallel to said shaft and said vertical shaft about its own axis to effect lateral adjustments of said head and wheel spindle.

5. An internal grinding machine comprising in combination, a base, a work supporting table movably mounted thereon, a column on said base, a carriage adjustable vertically on said column, a trunnion rotatably mounted within said carriage, a rotary wheel head spindle mounted for axial movement and angular adjustment within said trunnion, manually operated adjusting means on said trunnion to tilt said spindle about a horizontal axis in said trunnion to predetermined angular positions relative to the axis of rotation of said trunnion, a laterally adjustable wheel head supported at the lower end of said spindle on transverse ways provided therefor, means to manually adjust said wheel head predetermined distances laterally from the axis of rotation of said spindle and during rotation of said spindle, a planetary gearing system in said wheel adjusting means, a vertical shaft extending within said spindle to effect lateral movement of said wheel, a rotatably mounted casing enclosing said gearing, means to rotate said planetary gearing by rotation of said trunnion during operation of the machine, said rotation of said trunnion maintaining said vertical shaft and wheel head in fixed lateral position relative to the axis of rotation of said shaft, and manual means connected to said casing to adjust the rotative position of said casing to rotate said vertical shaft relative to the trunnion rotation and vary the lateral adjustment of said wheel head.

HENRY E. DURKEE.
